(57) **CLAIM**

The ornamental design for an optical element for vehicle lighthead, as shown and described.

DESCRIPTION

FIG. 1 is a front, top and right perspective view of an optical element for vehicle lighthead showing my new design; FIG. 2 is a top, rear and right perspective view thereof; FIG. 3 is a front elevation view thereof; FIG. 4 is a rear elevation view thereof; FIG. 5 is a left side elevation view thereof; FIG. 6 is a right side elevation view thereof; and,

FIG. 7 is a top plan view of the optical element for vehicle lighthead, wherein the bottom view is a mirror image thereof.

The optical element for vehicle lighthead have been shown separated and bound by dot-dash broken lines and a bracket to indicate indeterminate length.

The dot-dash broken lines in the figures show boundaries that form no part of the claimed design.
